GARMENT HANGER

Albert G. Wahl, Los Angeles, Calif.

Application April 12, 1943, Serial No. 482,727

1 Claim. (Cl. 223—88)

My invention relates to a garment hanger and has for its principal object to provide a simple, inexpensive and practical structure that may be conveniently and effectively employed for hanging garments, and, particularly, skirts, trousers and the like.

A further object of my invention is to provide a hanger of the character referred to wherein a pair of garment supporting fingers are adjustably mounted on the curved arm or cross bar of a conventional garment hanger, thus enabling skirts, trousers and the like of different sizes to be properly supported and hung from the rail or cross bar.

With the foregoing and other objects in view, my invention consists in certain novel features of construction and arrangement of parts which will be hereinafter more fully described and claimed and illustrated in the accompanying drawing, in which

Fig. 1 is an elevational view of a garment hanger constructed in accordance with my invention.

Fig. 2 is an enlarged vertical section taken on the line 2—2 of Fig. 1.

Figs. 3, 4 and 5 are elevational views of modified forms of the garment engaging fingers which are adjustably mounted upon the curved bar or rail of the hanger.

Fig. 6 is a horizontal section taken on the line 6—6 of Fig. 5.

Referring by numerals to the accompanying drawing and particularly to the form of hanger illustrated in Figs. 1 and 2, 10 designates the curved wooden rail or bar of a conventional garment hanger from the center of which projects upwardly the hook 11 which engages a rail or other suitable support.

Mounted for longitudinal adjustment upon the curved bar 10 to the sides of the hanger 11 are depending fingers 12, preferably formed of sheet material, such as cardboard, and after being cut to shape, the cardboard is folded on a medial transverse line so that the main body portions 13 of the fingers are of double thickness, and the outer edges of the fingers are curved outwardly as designed by 14 in order to provide curved rests or shoulders which receive the waist band and adjacent upper portion of a skirt.

By folding the material double to form the fingers 13, transverse loops 15 are formed at the upper ends of said fingers and immediately below said loops the walls of the finger are suitably connected to each other, preferably by means of staples 16.

The loops 15 receive the curved arm or rail 10 and said loops may be readily moved lengthwise of said rail thereby adjusting said fingers toward or away from each other for the accommodation of skirts of different sizes.

In Fig. 1, dotted lines *a* show the upper portion of a skirt resting upon the curved outer edges 14 of the supporting fingers.

The modified construction illustrated in Fig. 3 is particularly designed for engaging the lower ends of trouser legs for suspending same from the hanger and in this construction, the fingers 17 are formed from sections of cardboard or the like bent double to form loops 18 at their upper ends which loops are mounted for sliding movement on the rail 10 of the hanger.

Formed on the lower portion of the outer edge of each hanger is a series of upwardly presented hooks 20 and at the upper end of this row of hooks is formed a horizontally disposed shoulder 19, such construction being particularly effective in engaging the ends of the legs of trousers provided with the conventional cuffs.

In the modified construction illustrated in Fig. 25 4, the finger 21, preferably formed of cardboard bent double and provided at their upper ends with loops such as 22, which receive the curved arm 10 of the hanger, are provided on their outer edges with upwardly presented teeth 21 30 which tend to engage the fabric of the garments thereby holding the same in suspended position from the hanger.

In the modified construction illustrated in Figs. 5 and 6, the finger 24, formed from thin pliable material such as cardboard, is provided with a curved outer edge 25 upon which is adapted to rest the waist band and upper portion of a skirt and formed in the upper portion of the finger is a pair of spaced apertures 26 for the reception

40 of the curved arm 10 of the hanger, thus enabling the fingers to be adjusted lengthwise upon said arm and to maintain its position thereon after adjustment.

In the forms of hanger illustrated in Figs. 1 45 to 4 inclusive, the friction between the loops 15 and the curved arm 10 is sufficient to maintain the garment supporting fingers in their differently adjusted positions.

Thus, it will be seen that I have provided a 50 garment hanger particularly adapted for the hanging of skirts, trousers and the like, and which hanger is simple in structure, inexpensive of manufacture and very effective in performing the functions for which it is intended.

55 It will be understood that minor changes in the

size, form and construction of the various parts of my improved garment hanger may be made and substituted for those herein shown and described without departing from the spirit of my invention, the scope of which is set forth in the appended claim.

I claim as my invention:

The combination with a garment hanger having a curved rail, of garment supporting members mounted for longitudinal adjustment on the end portions of said rail, each member comprising a single piece of thin sheet material folded double on a medial line to form identical de-

pendent walls lying flat against each other fastening means passing through said walls a short distance below the line of fold, with those portions of the walls between the line of fold and fastening means spaced apart to form a flattened tube for snugly receiving and frictionally engaging the curved rail of the hanger and the walls below said tube and fastening means extending downwardly and outwardly from said tube to form a lobe shaped member of double thickness having a continuous arched upper edge for receiving and supporting garments.

ALBERT G. WAHL.
